4 Sheets-Sheet 3

Fig. 4.

This technical drawing illustrates a mechanical assembly, likely a component of a larger machine. The drawing is labeled with numerous reference numerals, including:

- 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 760, 761, 762, 763, 764, 765, 766, 767, 768, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, 2077, 2078, 2079, 2079, 2080, 2081, 2082, 2083, 2084, 2085, 2086, 2087, 2088, 2089, 2089, 2090, 2091, 2092, 2093, 2094, 2095, 2096, 2097, 2098, 2099, 2099, 2100, 2101, 2102, 2103, 2104, 2105, 2106, 2107, 2108, 2109, 2109, 2110, 2111, 2112, 2113, 2114, 2115, 2116, 2117, 2118, **APPARATUS FOR DISTRIBUTING MATERIALS
AND DEPOSITING METERED QUANTITIES
THEREOF INTO CONTAINERS**

Walter E. Saxe, Pasadena, Calif., assignor to The Conveyor Company, Los Angeles, Calif., a corporation of California

Application January 27, 1953, Serial No. 333,473

15 Claims. (Cl. 226—94)

The present invention relates to a method of and apparatus for distributing granular materials, the term "granular material" being intended to include any material composed of discrete, solid particles or granules. Examples of such materials are crushed ice, grains, flour, sand, gravel and the like. Because of the tendency of ice particles to freeze together and bridge across bin outlets, and the like, the present invention is of particular utility in the distribution of crushed ice, and will be considered in such connection hereinafter, as a matter of convenience, the invention originally having been embodied in a distribution system for crushed ice. Also, the present invention will be considered in connection with the packing of produce in crushed ice, as a matter of convenience, it being understood that the invention is not to be limited to distributing crushed ice, or to packing produce in ice, however, since it is susceptible of various other applications.

In packing vegetables, or other produce, in ice preparatory to shipment, it is conventional to place such vegetables in crates moving along a conveyor and to dump crushed ice into the crates at intervals from an overhead storage or supply bin, the latter being provided with valved outlets or discharge means at the points where crushed ice is to be placed in the crates. In such a conventional installation, the crushed ice in the storage or supply bin frequently refreezes to some extent, and frequently bridges across the outlets so that no crushed ice is discharged when the valves associated with the outlets are opened. Also, in conventional installations of this nature, all of the crushed ice frequently is discharged through one or a few of the outlets with the result that the remainder receive no ice, which is obviously undesirable.

In view of the foregoing, one of the primary objects of the present invention is to maintain the crushed ice in the supply bin in a fluid state by continuously circulating the ice around a closed path which embraces all of the discharge points. More particularly a primary object of the invention is to provide a distributing system which includes a supply bin having the form of a closed loop embracing all of the outlets, and which includes conveyor means in the bin for continuously circulating the ice around the closed loop. The crushed ice is circulated around the closed loop at a rate in excess of the rate of discharge of the ice through the outlets so that no outlet is ever starved, the circulation rate preferably being of the order of magnitude of three to four times the discharge rate.

While the supply bin of the invention may take various loop forms, it is preferably in the form of a rectangular loop with outlets along two sides thereof, conveyors for produce crates being located below and parallel to these two sides of the rectangular loop. Thus, the invention accommodates at least two packing conveyors, which is an important feature. If desired, additional packing

2

conveyors may be located beneath and parallel to the other two sides of the rectangular loop.

Another object is to provide a conveyor means for circulating the crushed ice around the rectangular loop 5 of the supply bin which includes screw conveyors respectively disposed in the four sides of the loop with the discharge end of each screw conveyor located adjacent the inlet end of the next.

Another object is to provide scale means connected 10 to the supply bin and including an indicator for indicating the weight of crushed ice in the bin at all times so that additional crushed ice may be supplied to the bin as required to replace the ice discharged through the outlets.

15 The distributing system includes a supply means for replenishing the crushed ice discharged from the supply bin, the supply means including an ice crusher, for example, located in an ice house, or the like. An object in this connection is to provide a scale means which 20 includes a remote indicator located in the ice house so that the operator of the distributing system can readily determine the weight of crushed ice in the supply bin and can feed block ice to the ice crusher as required. More broadly, the operator can cause the supply means 25 to deliver crushed ice to the supply bin.

Another object is to provide automatic means for replenishing the crushed ice in the supply bin, such automatic means including actuating means controlled by the scale means for actuating the supply means whenever 30 the weight of crushed ice in the supply bin falls below a predetermined minimum.

An important object is to provide a discharge means 35 for discharging metered quantities of the crushed ice from the supply bin into the produce crates on the conveyors.

Another object is to provide a metering discharge means which includes a conduit communicating with the supply bin and a valve movable transversely of the conduit, the valve including a first gate traversing the 40 conduit and having a first aperture adapted to register with the conduit, and including a second gate traversing the conduit downstream from the first gate and having a second aperture adapted to register with the conduit, the valve being movable from a first position wherein the first aperture registers with the conduit to a second position wherein the second aperture registers with the conduit. With this construction, the conduit section or zone between the two gates acts as a metering chamber, this 45 metering chamber filling up with crushed ice when the valve is in its first position and being emptied when the valve is moved from its first position to its second position.

Another object is to provide a metering discharge means 50 wherein the conduit section or zone between the two gates of the valve diverges downwardly so that any possibility that the crushed ice may stick in the metering chamber is minimized.

Another object is to provide an actuating means including a first switch actuatable by crates passing a given 55 point on one of the conveyors and a second switch actuatable by movement by a particular discharge valve to its second position for moving that valve to its second position when a crate on the conveyor arrives at a position to receive a metered quantity of crushed ice, and for subsequently moving the valve back to its first position to recharge the metering chamber.

The foregoing objects and advantages of the present invention, together with various other objects and advantages thereof which will become apparent, may be obtained with the exemplary embodiment of the invention which is illustrated in the accompanying drawings 60 and which is described in detail hereinafter.

Referring to the drawings:

Fig. 1 is a side elevational view of a distributing system which embodies the invention;

Figs. 2, 3 and 4 are sectional views respectively taken along the arrowed lines 2—2, 3—3 and 4—4 of Fig. 1 of the drawings, Fig. 3 being a fragmentary view;

Fig. 5 is an enlarged, fragmentary sectional view showing a metering discharge means of the invention;

Fig. 6 is a view similar to Fig. 5 with various elements of the discharge means in other operating positions;

Figs. 7 and 8 are sectional views respectively taken along the arrowed lines 7—7 and 8—8 of Fig. 5; and

Fig. 9 is a wiring diagram of the invention.

Referring particularly to Figs. 1 to 4 of the drawings, the distributing system of the invention includes a frame 10 which is rectangular with two long sides and two short sides in the particular construction illustrated, although other shapes may be used, as will be indicated hereinafter. The frame 10 may be of any suitable construction and will be described only generally as including an overhead section 11 supported by rows of columns 12 along the respective long sides thereof. Conveyors 13 extend along the respective long sides of the rectangular frame 10 outside the rows of columns 12, the conveyors 13 being adapted to convey articles, such as produce crates 14, in the direction of the arrows 15. Each conveyor 13 is provided with spaced high-speed sections 16 for the purpose of spacing the crates 14 apart, as will be discussed hereinafter, the high-speed sections 16 operating at a higher linear speed than the other sections of the conveyors 13. Three high-speed sections 16 are shown in the particular construction illustrated, although this number may be varied, as will be discussed hereinafter.

Mounted on the frame 10 in a manner to be described hereinafter is an auxiliary frame 20 of any suitable construction which carries a storage or supply hopper or bin 21. This bin takes the form of a closed loop which is rectangular in the particular construction illustrated, the frame 10 being rectangular; as hereinbefore indicated to conform thereto. However, other frame and closed-loop bin shapes may also be used, it being understood that the invention is not to be limited to rectangular shapes. The rectangular loop formed by the bin 21 encircles the columns 12 of the frame 10, as best shown in Fig. 2 of the drawings, so that the two long sides of the rectangular bin loop are disposed above the respective conveyors 13. Each long side of the rectangular loop defined by the bin 21 is provided with discharge means 22 for discharging crushed ice from the bin into the crates 14 on the conveyors 13, there being three discharge means 22, respectively corresponding to the three high-speed sections 16 of each conveyor 13, along each long side of the bin loop. The structure and operation of the discharge means 22 will be considered in more detail hereinafter.

Each side of the rectangular bin 21 is troughlike in cross section, as best shown in Fig. 4 of the drawings, the top of the bin preferably being open, although it may be closed if desired. Within the bin 21 is a conveyor means 23 for continuously circulating the crushed ice or other material around the closed loop defined by the bin so as to maintain the crushed ice in a fluid state, thereby preventing refreezing of the ice particles and preventing the formation of bridges across the various discharge means 22. The rate of circulation of the crushed ice by the conveyor means 23 exceeds the rate of discharge of the crushed ice into the crates 14 by the various discharge means 22 so that no discharge means is ever starved. Preferably, the rate of circulation around the bin loop by the conveyor means 23 is of the order of magnitude of three or four times the rate of discharge through the discharge means 22 to insure maintenance of the fluidity of the crushed ice and to insure an adequate supply of crushed ice to each and every discharge means 22.

In the particular construction illustrated, the conveyor means 23 comprises four screw conveyors 24 respectively

disposed in the bottoms of the four sides of the rectangular loop formed by the bin 21, the lengths of the screws 24 being commensurate with the lengths of the sides of the rectangular bin loops. The bottoms of the trough-like sides of the bin are hemi-cylindrical to receive the screws 24, the latter being mounted in suitable bearings in a manner not specifically shown. The screws 24 are driven by motors 25 respectively mounted on the four corners of the rectangular bin loop, as best shown in Fig. 2 of the drawings. It will be understood that the screws 24 are so arranged and driven that the discharge end of each screw is adjacent the inlet end of the next screw so that the desired circulatory movement of the crushed ice around the bin loop is obtained.

Considering the manner in which the auxiliary frame 20 carrying the bin 21 is mounted on the main frame 10, the invention provides a scale means 30 which supports the auxiliary frame 20 and bin 21 and which includes an indicator 31, for indicating the weight of crushed ice in the bin. As best shown in Fig. 4 of the drawings, two floating horizontal shafts 32 are located just inside the columns 12 of the main frame 10, and, as best shown in Fig. 1, extend the length of the frame. Each shaft 32 carries a plurality of inwardly facing cranks 33, each crank being supported from above by a rod 34 pivotally connected thereto and connected to the overhead section 11 of the main frame 10. Each crank 33 is also connected to the auxiliary frame 20 supporting the bin 21 by a rod 35, each rod 35 being pivotally connected to the corresponding crank and being connected at its lower end to the auxiliary frame. Two of the cranks 33 on the respective shafts 32 are provided with inwardly facing arms 36 universally interconnected at their inner ends by a joint 37. Pivotally connected at its lower end to the joint 37 is a link 38 which is pivotally connected at its upper end to an intermediate point on a scale beam 39, the latter being pivotally connected to the lower end of a rod 40 which is connected at its upper end to the overhead section 11 of the main frame 10. Pivotally connected to the beam 39 on the opposite side of the link 38 from the rod 40 is a strap 41 leading to the indicator 31. The latter is a conventional scale head having a drum 42 around which the strap 41 is wound and having connected thereto a weight arm 43. As will be apparent, with this linkage, any increase in the weight of the crushed ice in the bin 21 will cause the weight arm 43 to swing upwardly to produce an indication of increasing weight on the indicator 31.

In order to enable the indicator 31 to indicate directly the net weight of crushed ice in the bin 21, means 50 for balancing out the tare weight of the auxiliary frame 20, the bin 21, the discharge means 22, the conveyor means 23, and associated mechanism, is provided. The means 50 includes a tare beam 51 pivotally connected to the lower end of a rod 52 which is connected to the overhead section of the frame 10 at its upper end. The beam 51 is pivotally connected to the beam 39 by a link 53 and is provided with a sliding weight 54 by means of which the tare weight may be balanced out. Thus, the indicator 31 indicates directly the net weight of the crushed ice in the bin 21, which is an important feature.

Continuing to refer to Fig. 4 of the drawings, a supply means 60 for replenishing the crushed ice discharged by the discharge means 22 is provided. Although the supply means 60 may take various forms, it is illustrated diagrammatically in the drawings as including an ice crusher 61 which discharges into a conduit or a conveyor 62 leading to the bin 21 from an ice house, or the like, in which the ice crusher is disposed, the crushed ice being discharged into the open topped bin at any suitable point for closed-loop circulation by the conveyor means 23. The ice crusher 61 is adapted to be supplied with block ice 63 by a conveyor 64 driven by a motor 65.

Ordinarily the ice house, or other location for the ice crusher 61, is some distance from the distributing system

for the crushed ice and a feature of the invention is to provide adjacent the ice crusher 61, or other supply means, a remote indicator 66 similar to or replacing the indicator 31. The remote indicator 66 is actuated by a Selsyn system which includes a transmitter 67 driven by the drum 42 and connected to a receiver 68 which drives the remote indicator, the connection between the transmitter and the receiver being indicated diagrammatically at 69. Thus, the operator of the apparatus can start the conveyor 64 to deliver additional blocks of ice to the crusher 61 whenever the indication provided by the remote indicator 66 drops to a predetermined minimum, thereby maintaining an adequate supply of ice in the bin 21. Also, the invention provides automatic means for this purpose. In the particular construction illustrated, the motor 65 is adapted to be controlled by another Selsyn receiver 70 which is connected to the transmitter 67 in parallel with the receiver 68. Thus, whenever the weight of crushed ice in the bin 21 falls below a predetermined minimum, the conveyor motor 65 is automatically energized to deliver additional blocks of ice to the crusher 61. Thus, the supply of crushed ice in the bin 21 is automatically maintained within predetermined limits, which is an important feature.

Referring to Figs. 5 to 8 of the drawings, illustrated in detail therein is one of the discharge means 22, all of the discharge means being similar so that only one of them needs be described in detail. The discharge means 22 illustrated in Figs. 5 to 8 includes a depending conduit 80 which is carried by the bin 21 and which is of square cross section in the particular construction illustrated, the conduit registering with a complementary discharge or outlet opening 81 in the bottom of the bin. Preferably, the conduit 80 is made up of three sections, including an upper section 82 welded or otherwise, secured to the bin 21 in registry with the discharge opening 81, the upper section 82 having laterally extending flanges 83 on opposite sides thereof, as best shown in Fig. 8. Below the upper section 82 is an intermediate, downwardly diverging section 84, having upper flanges 85 registering with the flanges 83. The spaces between the flanges 83 and 85 form tracks 86 for an upper or first gate 87 of a metering valve 88, as will be discussed in more detail hereinafter. Below the intermediate section 84 of the conduit 80 is a member 89 to which a lower section 90 of the conduit is suitably secured, as by welding. The intermediate section 84 is provided with lower flanges 91 registering with flanges 92 on the member 89 and providing tracks 93 for a lower gate 94 of the metering valve 88.

In the particular construction illustrated, the intermediate section 84, which is located between the gates 87 and 94, is secured in place by welding the flanges 83 and 85 together and by welding the flanges 91 and 92 together, although the intermediate section may be secured in place in other ways. In addition to the tracks 87 and 93 for the metering valve 88, tracks or rails 95 on which the valve rests are provided, these tracks or rails being suitably secured to the conduit 80, or the bin 21, in a manner not specifically shown.

The metering valve 88 itself has the form of a rectangular, box-like, structure in the particular construction illustrated, the upper and lower walls of this structure being formed by the upper and lower gates 87 and 94, respectively. The two gates 87 and 94 are interconnected at their ends to make the metering valve 88 an integral unit. The valve may be moved transversely of the conduit 80 along the tracks hereinbefore discussed in any suitable manner, as by a reciprocating hydraulic motor 96 pivotally connected to a bracket 97 on the bin 21 and having a piston rod 98 pivotally connected to the valve 88.

The upper gate 87 is provided with an aperture 102 therein adapted to register with the conduit 80, and the lower gate 94 is provided with an aperture 103 therein which is also adapted to register with the conduit 80.

but which is spaced or offset from the aperture 102 so that when one of the apertures is in full registry with the conduit the other is out of registry therewith. When the first or upper aperture 102 is in registry with the conduit 80, the valve 88 is regarded as being in its first position, this position being shown in Fig. 5 of the drawings. When the valve 88 is in a second position thereof, the aperture 102 is out of registry with the conduit, and the aperture 103 is in full registry therewith. This second position of the valve 88 is not shown in the drawings, but it will be understood that it is a position somewhat to the left of the position shown in Fig. 6 of the drawings.

Considering the operation of the discharge means 22, when the valve 88 is in its first position, as shown in Fig. 5 of the drawings, the intermediate section 84 of the conduit 80 fills with crushed ice. This intermediate section forms what may be termed a metering chamber the lower end of which is closed by the lower gate 94 when the valve is in its first position. As the valve 88 is moved from its first position toward its second position, as shown in Fig. 6 of the drawings, the crushed ice in the metering chamber defined by the intermediate section 84 falls through the lower aperture 103 into the lower section 90 of the conduit 80. The adjacent edges 104 and 105 of the apertures 102 and 103 are laterally spaced or offset, so that, even though both the apertures 102 and 103 are in partial registry with the conduit 80 simultaneously, no additional crushed ice can enter the metering chamber as the valve 88 is moved toward its second position because passage of ice into the metering chamber through the upper aperture 102 is prevented by the ice supported by the lower gate 94 adjacent to the edge 105. Consequently, each time the metering valve 88 is moved from its first position to its second position, a metered quantity of crushed ice, equal in volume to the volume of the metering chamber defined by the intermediate section 84, is dispensed, which is an important feature of the invention. As previously mentioned, the metering chamber defined by the intermediate section 84 diverges downwardly so that, even if some refreezing occurs in the metering chamber tending to cause the ice particles to adhere, the charge of ice in the metering chamber will nevertheless fall freely into the lower section 90 of the conduit 80 when the valve 88 reaches its second position. As will be apparent, as the valve 88 is restored to its first position, an additional charge of ice falls into the metering chamber through the upper aperture 102, the ice falling into the metering chamber in this fashion falling onto the lower gate 94 adjacent the edge 105 so that little or none of this ice can fall into the lower section 90 of the conduit. By the time the metering valve 88 is returned to its first position, the metering chamber defined by the intermediate section 84 is fully charged with crushed ice because of the state of fluidity maintained in the bin 21 by the conveyor means 23, as hereinbefore discussed.

Considering now the manner in which each discharge means 22 is actuated, it will be noted from Fig. 1 of the drawings that associated with the conveyors 13 below each discharge means 22 is a first switch 111 mounted on the corresponding conveyor 13 in a position to be closed by one of the crates 14. As shown in Figs. 5 and 6, each discharge means 22 has associated therewith a second switch 112 which is normally closed, i. e., which normally tends to close, but which is held open by engagement with the underside of the valve 88. However, when the valve 88 reaches its second position, the second switch 112 disengages the trailing end 113 of a lug 114 on the valve 88, and moves to its closed position momentarily, as will be discussed hereinafter.

Referring now to Fig. 9 of the drawings, illustrated therein is an electrical circuit controlling one of the discharge means 22. This circuit includes a device, shown as a solenoid valve 115, for controlling the hy-

draulic motor 96, or other actuator, for the corresponding valve 88. The first switch 111 associated with each discharge means 22 is connected in series with the solenoid valve 115 so that when a crate 14 arrives at a position below the discharge means, the corresponding switch 111 is closed to energize the corresponding solenoid valve 115. This energizes the corresponding hydraulic motor 96 to start the valve 88 on its way to its second position, thereby discharging a metered quantity of crushed ice into the crate. The corresponding second switch 112 is connected in series with the switch 111 and in series with a relay 116, the latter being in parallel with the solenoid valve 115. The relay 116 operates a switch 117 in series with the switch 111 and the solenoid valve 115, and operates a holding switch 118 connected in series with itself and in series with the switch 111. With this circuit, when the metering valve 88 reaches its second position, the switch 112 closes to energize the relay 116. Energization of the relay 116 in this manner results in closure of the holding switch 118 and in opening the switch 117, whereby the solenoid valve 115 is de-energized so that it is restored to its initial position to start the valve 88 from its second position back toward its first position again. Thus, the closure of the switch 112 is momentary only, but the holding switch 118 maintains the relay 116 energized to de-energize the solenoid valve 115 until such time as the switch 111 opens upon disengagement by the crate into which crushed ice was discharged. As soon as the switch 111 opens, the relay 116 is de-energized to reset the circuit in preparation for another cycle when the next crate 14 engages the switch 111 of the discharge means in question. In order to insure that each crate 14 disengages the switch 111 before the next crate engages it, the high-speed conveyor section 16 associated with discharge means 22 under consideration spaces the crates apart.

Considering the over-all operation of the distributing system of the invention briefly, the crushed ice in the bin 21 is constantly maintained in a fluid state because of the continuous circulation thereof around the bin 21 by the conveyor means 23. Thus, any tendency of the ice particles to freeze together, and thus possibly form bridges over the discharge openings 81, is eliminated, which is an important feature of the invention. The weight of ice in the bin 21 is constantly indicated by the scale means 39, so that the operator of the system may feed additional block ice to the crusher 61 as required to replenish the supply in the bin 21. Alternatively, the block ice may be fed to the crusher automatically in the manner hereinbefore discussed. As each crate 14 arrives at each discharge station, it actuates the circuit hereinbefore described to receive a charge of crushed ice from the corresponding discharge means 22, a charge of ice being dispensed each time the corresponding metering valve 88 is moved from its first position to its second position, as hereinbefore discussed. With the particular construction shown, wherein three discharge means 22 are spaced apart along each conveyor 13, a charge of ice may be placed in the bottom of each crate 14, a layer of produce placed on this charge of ice, a second charge of ice placed on top of the first layer of produce, an additional layer of produce placed on top of the second charge of ice, and the crate topped off with ice by the last discharge means. However, it will be understood that other procedures and arrangements may be utilized without departing from the invention.

Although I have disclosed an exemplary embodiment of my invention herein for purposes of illustration, and have disclosed a particular application of such embodiment, it will be understood that the invention is susceptible of various other applications and that various changes, modifications and substitutions may be incorporated in the embodiment disclosed without necessarily departing from the spirit of the invention, as defined by the claims which follow.

I claim as my invention:

1. In a distributing system for a granular material, the combination of: a bin for the material having the form of a closed loop; conveyor means in said bin for continuously circulating the material around said loop to maintain it in a fluid state, said conveyor means being continuous throughout said loop; means for discharging the material from said bin at one or more points on said loop; and scale means connected to said bin and including an indicator for indicating the weight of material in said bin.
2. In a distributing system for a granular material, the combination of: a bin for the material having the form of a closed, multisided loop; conveyor means in said bin for continuously circulating the material around said closed loop, comprising a screw conveyor in each of said sides of said loop and extending substantially the full length thereof, each of said screw conveyors having a discharge end adjacent the inlet end of the next screw conveyor in said loop, whereby said conveyor means is continuous around said loop; means for discharging the material from said bin at one or more points on said loop; and scale means connected to said bin and including an indicator for indicating the weight of material in said bin.
3. The distributing system set forth in claim 2 wherein said loop is rectangular.
4. In a distributing system for a granular material, the combination of: a bin for the material having the form of a closed loop; conveyor means in said bin for continuously circulating the material around said closed loop, said conveyor means being continuous around said loop; means for discharging the material from said bin at one or more points; and scale means connected to said bin and including an indicator for indicating the weight of material in said bin.
5. A distributing system according to claim 4, including supply means for delivering material to said bin, said supply means being spaced from and communicating with said bin, said scale means including a remote indicator located at said supply means.
6. The distributing system defined in claim 4, including in addition: supply means for delivering material to said bin; and actuating means controlled by said scale means for actuating said supply means whenever the weight of material in said bin falls below a predetermined minimum.
7. A distributing system as defined in claim 1, including in addition: supply means for delivering material to said bin; and actuating means controlled by said scale means for actuating said supply means to deliver material to said bin whenever the weight of material in said bin falls below a predetermined minimum.
8. In a distributing system for a granular material, the combination of: a bin for the material having the form of a closed loop; conveyor means in said bin for continuously circulating the material around said loop to maintain it in a fluid state, said conveyor means being continuous throughout said loop; and discharge means communicating with said bin for discharging the material from said bin in metered quantities at one or more points on said loop, said discharge means including a conduit communicating with said bin, a valve movable transversely of said conduit including a first gate traversing said conduit and having a first aperture adapted to register therewith, and including a second gate traversing said conduit downstream from said first gate and having a second aperture adapted to register with said conduit, said valve being movable from a first position wherein said first aperture registers with said conduit to a second position wherein said second aperture registers therewith; and actuating means for moving said valve between said first and second positions.
9. In a distributing system for a granular material, the combination of: a bin for the material having the form of a closed loop; conveyor means in said bin for con-

tinuously circulating the material around said loop to maintain it in a fluid state; discharge means communicating with said bin for discharging the material from said bin in metered quantities at one or more points on said loop, said discharge means including a valve movable between first and second positions to meter predetermined quantities of material from said bin; a conveyor for articles adapted to receive metered quantities of material from said discharge means; and actuating means, including a first element actuatable by articles on said conveyor and a second element actuatable by movement by said valve to said second position, for moving said valve to said second position when an article on said conveyor arrives at a position to receive a quantity of material from said discharge means and for subsequently moving said valve back to said first position when it arrives at said second position.

10. In a distributing system for a granular material, the combination of: a bin having metering discharge means which includes a valve movable between first and second positions to meter predetermined quantities from said bin; a conveyor for articles adapted to receive metered quantities of material from said discharge means; and actuating means, including a first element actuatable by articles on said conveyor and a second element actuatable by movement of said valve to said second position, for moving said valve to said second position when an article on said conveyor arrives at a position to receive a quantity of material from said discharge means and for subsequently moving said valve back to said first position in response to its arrival at said second position.

11. A distributing system as defined in claim 10 wherein in said first and second elements are first and second switches, said actuating means including an actuator connected to said valve, and including a device for energizing said actuator, said actuating means further including a third switch in series with said first switch and said device, and still further including a holding relay in series with said second switch for opening said third switch to de-energize said device when energized by closure of said second switch.

12. In a distributing system for a granular material, the combination of: a bin for the material having the form of a closed loop; conveyor means in said bin for continuously circulating the material around said loop to maintain it in a fluid state, said conveyor means being continuous throughout said loop; and means for discharging the material from said bin at one or more points on said loop.

13. In a distributing system for a granular material having a tendency to cake, the combination of: a bin for the material having the form of a closed, rectangular loop; conveyor means in said bin for continuously circulating the material around said loop, comprising a conveyor in each of the sides of said loop and extending substantially the full length thereof, each of said conveyors having a discharge end immediately adjacent the inlet

end of the next conveyor in said loop, whereby said conveyor means is continuous throughout said loop to maintain the material in a fluid state at all points therein; means for discharging the material from said bin at one or more

5 points on at least one side of said loop; a conveyor beneath and parallel to said one side of said loop to receive material from said discharging means; and means, including scale means connected to said bin, for supplying additional material to said bin whenever the weight of ma-

10 terial in said bin falls below a predetermined minimum.

14. In a distributing system for a granular material, the combination of: a bin having metering discharge means which includes a metering valve movable between first and second positions to meter a predetermined quantity of the material from said bin; means for moving said metering valve from said first position to said second position; and means actuatable by said metering valve and responsive to its arrival at said second position for returning said metering valve to its first position.

15. In a discharge means for discharging metered quantities of material from a bin, or the like, the combination of: a conduit communicating with said bin; a valve movable transversely of said conduit, including a

25 first gate traversing said conduit and having a first aperture adapted to register with said conduit, and including a second gate traversing said conduit downstream from said first gate and having a second aperture adapted to register with said conduit, said valve being movable be-

30 tween a first position wherein said first aperture registers with said conduit and a second position wherein said second aperture registers therewith; and actuating means for moving said valve between said first and second positions, including means actuatable by said valve and re-

35 sponsive to the arrival of said valve in said second position for returning said valve to said first position.
